(57) CLAIM

The ornamental design for a side mirror cover, as shown and described.

DESCRIPTION

FIG. 1 is a front perspective view of the side mirror cover with strap;

FIG. 2 is a rear perspective view of the side mirror cover with strap;

FIG. 3 is a front elevation view of the side mirror cover with strap;

FIG. 4 is a rear elevation view of the side mirror cover with strap;

FIG. 5 is a top elevation view of the side mirror cover of FIG. 1, the bottom view being a mirror image of the top view;

FIG. 6 is a right side view of the side mirror cover of FIG. 1; and,

FIG. 7 is a left side view of the side mirror cover according to the implementation of FIG. 1.

The broken lines in FIGS. 1 and 2 show an automobile mirror and form no part of the claimed design.
